UNITED STATES PATENT OFFICE.

WALLACE L. HARDISON, OF ST. PETERSBURG, PENNSYLVANIA.

IMPROVEMENT IN PACKERS FOR OIL-WELLS.

Specification forming part of Letters Patent No. 171,616, dated December 28, 1875; application filed December 3, 1875.

To all whom it may concern:

Be it known that I, WALLACE L. HARDISON, of St. Petersburg, in the county of Clarion and State of Pennsylvania, have invented certain new and useful Improvements in Packer for Oil-Well; and I do hereby declare that the following is a full, clear, and exact description thereof, which will enable others skilled in the art to which it appertains to make and use the same, reference being had to the accompanying drawings, and to the letters of reference marked thereon, which form a part of this specification.

Figure 1 is a vertical section of my improved packer, the telescopic joint and flexible packing being drawn out to their full length. Fig. 2 is another vertical section, showing the flexible packing under a state of compression. Fig. 3 is a cylinder of cast metal to be used in place of cylinder C, Figs. 1 and 2; and Fig. 4 is a top view of cap C' and bag E.

In the drawings, A represents the well within which the packer is to be used. B represents the upper section of an anchor. B' is a cap, provided with an internal thread, which fits the upper end of the section B. This cap has two ribs, b and b', upon its outer side, and a rib, c, upon its inner surface. C is a case or cylinder, of such size as to fit closely and slide freely within the rib c. c¹ is a rib on the outside of this cylinder C. C' is a cap attached to the upper end of cylinder C, and having one or more openings, c², for the insertion of a pumping-tube, D, and a steam-tube or gas-tube, D'. There may be one, two, or more of these tubes arranged in cap C', as may be found desirable.

From the above description it will be seen that the cylinder C and section B of the anchor form a sort of telescopic joint, and that the pipe D or pipes D D' may be let down into the section B of the anchor, the cylinder C sliding within the cap C' for that purpose.

E E' is a packing-bag, of some flexible material, either of a heavy canvas, with its ends made tapering in form, as shown at E' E', Fig. 1, or, what would be preferable, a bag woven or knitted, with ends formed tapering in the process of manufacture. The lower end of the bag is firmly secured to cap B', preferably by tying or wiring it (the bag) in the groove be-

tween the ribs b b'. The upper end of the bag is firmly secured to cap C'. (See Fig. 3.) I usually tie or wire this upper end both above and below the cap.

As shown in the drawings, the cylinder C is of such diameter as to nearly fill the bore of the well—that is, in a well of five and one-half inches inside diameter, I would use a cylinder of four and a half inches outside diameter, leaving an annular space of half an inch around the cylinder. The rib b' is about five inches in diameter, the rib b being five and a quarter inches in diameter. The ribs c and c¹ are each about one-eighth of an inch in width. The object in making rib b of greater diameter than rib b' is to insure that the material used in winding the end of the bag upon the cap B' shall not come in contact with the wall of the well when the packer is being lowered to place, as such contact might destroy or injure the cord or wire. In practice, I usually make the cylinder C about four feet long.

In putting my packer into operation I attach to the lower end of section B of the anchor a perforated pipe of such length as will support the packer at the desired point, and attach to the cap C' the pumping-tube D and gas-tube D', or such other tubes as may be desired, and let the tubes and packer down into the well, connecting the succeeding lengths of tube as they descend in the usual manner.

The central portion E of the bag is of about the same external diameter as the bore of the well, which it fits closely, and when the lower end of the anchor reaches the bottom of the well the weight of the tube D or tubes D D' forces cylinder C into the section B of the anchor. As the caps B' C' are thus made to approach each other the bag E E' is compressed, substantially as indicated in Fig. 2, until the annular space between the cylinder and the wall is filled practically air-tight and watertight with the folds of the bag.

In consequence of the tapering form of the ends of the bag, and the thickness of the material of which it is composed, the ends of the bag, even under heavy pressure, will ordinarily retain their tapering form; hence, the bag will not double back upon or around the cap in such manner as to interfere with a proper condensation of the packing around the cylinder,

or with the withdrawal of the packer from the well.

In Fig. 4 I have shown a cylinder, I, which I design making of a single piece of metal, having a rib, i, at the upper end, over which to receive the bag, and a rib, i', at the lower end, to lift the anchor by; and in order that the cap B' of the anchor may pass over the upper end of the cylinder, I propose to either make the rib i thinner than the rib i', or make the upper end of the cylinder enough smaller than the lower end to pass through cap B'; or I can make either of these ribs removable, so that it can be taken off to put on the cap B'. I' I' are passages or pipes through this cylinder, provided with screw-threads to receive the ends of the tubes which are to be used above or below the packer.

What I claim is—

1. The cylinder C and tube D or tubes D D',

sliding within the section B of the packer, in combination with a flexible packing, compressed between the cylinder and the wall of the well, substantially as set forth.

2. The packing-bag E E', having its ends made tapering, in combination with the anchor B and the sliding cylinder C, substantially as set forth.

3. The cylinder I, Fig. 4, made in one piece, and provided with ribs i i', and a passage or passages, I' I', for the oil or oil and gas, substantially as set forth.

In testimony that I claim the foregoing as my own I affix my signature in presence of two witnesses.

WALLACE L. HARDISON.
